UNITED STATES PATENT OFFICE

2,087,788

METHOD OF TREATING SOAP

Adolph F. Thal, Elmhurst, Ill.

Application August 2, 1934, Serial No. 738,073

1 Claim. (Cl. 87—16)

This invention relates to a process for treating soap which avoids a number of manipulative steps and processes which have heretofore been regarded as necessary in the production of soaps, particularly colored and perfumed soaps, the employment of my process not only quickening the final production of the product but securing great saving in the expense of the heretofore employed manipulative steps and consequently a saving in the cost of labor and in the consumption of power and heat.

At the present time the practice is to pump the upper layer of finished soap from the soap kettle to a storage tank from which it is drawn as needed for the next operation which comprises first cooling the soap and then drying the soap. The soap is drawn from the storage tank into a mixer, commonly called a crutcher and in the crutcher any materials which can properly be added at this stage are mixed with the soap. These materials usually consist of sodium silicate, soda ash or other alkali fillers. Such fillers are added only when a laundry flake soap is desired and if the soap is to be used for the production of toilet soap, the addition of fillers in the crutcher is omitted and the soap is run directly from the storage tank to chilling rolls.

The chilling rolls serve the purpose of solidifying and cooling the hot soap which comes either directly from the storage tank or from the crutcher. The soap is removed from the chilling rolls in the form of ribbons which are dropped onto a conveyer and conveyed to a belt or tunnel dryer where a hot air circulation removes the desired amount of water. However, in a belt or tunnel dryer the drying of the soap is not uniform, the inside of the flakes remaining moist and the outside drying excessively and forming a skin, this skin effect being the formation of a very hard dry skin on the outer surface of each chip, the interior of the chip being considerably higher in moisture content.

To partially equalize the moisture throughout the flakes dried in the belt or tunnel dryer, the chips are conveyed to a storage bin where they are stored for a period varying from 12 to 48 hours. During the storage the moisture from the interior of each chip diffuses to a certain extent to the hard dry outer skin and makes the moisture distribution more uniform.

After the moisture content has been partially equalized in the storage bins the soap flakes are mixed with perfume and coloring matter. The coloring matter and perfume are added in a mechanical agitator in which the color and per-

fume is distributed over the exterior of the chips. In order to distribute the coloring matter and perfume uniformly throughout the flakes it is necessary to mill the colored and perfumed chips and for this purpose the chips are run through a mill in which they are ground between either granite or steel rollers with a result that the coloring matter and perfume is dispersed throughout and incorporated in the soap. A further purpose of milling is to completely eliminate the skin effect by grinding and mixing between the rollers until a homogeneous product is obtained.

After this step the soap is ready to be put into its final form and if bar soap is desired the chips are conveyed to a plodder in which a packing screw presses the flakes into solid form and extrudes the solid soap through its outlet opening, the extruded soap being subsequently stamped into bars.

The primary object of the present invention is to avoid the majority of steps necessary in present soap drying processes by avoiding the necessity of cooling the soap before being dried and by drying the soap in a vacuum drum dryer in which the soap is cooled, dried and flaked without "skin effect" and can be immediately formed into cakes, thereby avoiding the necessity of equalizing the moisture content in the soap flakes by storing them in a bin and subsequently milling them.

Another object of the present invention is to provide, in the production of colored and perfumed soaps, a process in which the coloring matter and perfume can be added to the soap before it is dried and while still liquid. This eliminates the necessity of mixing the soap chips with coloring matter and perfume and thereafter milling the chips to secure a uniform distribution of the perfume and coloring matter.

Another object of the present invention is to provide such a process for drying, coloring and perfuming soaps in which a superior soap is produced in that the soap has a more uniform and accurately controlled moisture content and further in that the coloring matter and perfume is added while the soap is liquid and therefore more intimately united with the soap.

Another purpose of the present invention is to provide such a process which involves the continuous handling of the soap from the crutcher to the final product, the outlet of the crutcher being connected directly to the inlet of the vacuum dryer and the outlet from the vacuum dryer being directly connected to the plodder where

55

bar soap is desired or being connected with a suitable continuous discharge valve where flake soap is desired.

Another aim of the present invention is to provide such a process in which the soap is dried on small high-speed drums under vacuum thereby permitting large volumes of soap to be dried in a very short time and with very little apparatus.

Another purpose of the present invention is to provide such apparatus which will reduce labor cost and which can be operated with less power and heat than has been required in prior processes and in which a reduced amount of floor space is necessary for the equipment.

15 A further aim of the present invention is to provide a feeding hopper for the drying drums which has sealed contact with the drums and permits of employing atmospheric pressure on the liquid soap in the feeding hopper, or any desired 20 vacuum or pressure thereon without breaking the vacuum in the drying chamber of the vacuum drier.

In the accompanying drawings:

25 Fig. 1 is a simplified vertical section through a crutcher, vacuum double drum dryer and plodder suitable for carrying out my process in making bar soaps.

30 Fig. 2 is a vertical longitudinal section through the vacuum dryer shown in Fig. 1 and showing its connection to the plodder.

35 Fig. 3 is a vertical transverse section taken on line 3—3, Fig. 2.

Fig. 4 is a fragmentary vertical section taken on line 4—4, Fig. 2.

35 Fig. 5 is a fragmentary horizontal section taken on line 5—5, Fig. 6.

Fig. 6 is a fragmentary vertical enlarged section taken on line 6—6, Fig. 3.

40 Fig. 7 is a fragmentary vertical transverse section, on an enlarged scale, through the scraper blades and one of the drying drums.

Fig. 8 is a fragmentary side elevation of the 45 scraper blades taken on line 8—8, Fig. 7.

Fig. 9 is a vertical section through a continuous 45 discharge valve which is substituted at the outlet of the vacuum dryer for the plodder C when flaked soap is desired instead of bar soap.

In accordance with the present invention the liquid soap and the desired amounts of coloring 50 matter and perfume are fed to a crutcher A. The outlet of the crutcher connects directly with the inlet of a vacuum double drum dryer indicated at B, in which, by drying under vacuum, the soap is dried without skin effect and loss 55 of perfume to any appreciable extent or deterioration of color and from which it is discharged directly to a plodder C which presses the uniformly dried flakes into solid form and delivers the soap from its outlet nozzle after which the 60 delivered soap can be cut and pressed into cakes. If flaked soap is desired the soap flakes are discharged from the vacuum double drum dryer through a continuous discharge valve D from which the soap can be directly packaged.

65 The crutcher A can be of any usual form and as shown comprises a jacketed cylindrical outer shell 15 having a closed bottom and an open top and in which a vertical screw 16 is journaled. This screw works in an inner tubular shell 17 70 which is double walled and open at its top and bottom so that the screw constantly moves the material up the center of the inner shell 17 over the top of the inner shell and down between the two shells, thereby keeping the liquid soap constantly in motion. In order to keep the soap

liquid, steam is supplied to the double walled inner shell 17 and to the jacketed outer shell 15. The screw is turned through suitable gearing 19 arranged at the top of the outer shell 15 and driven by a pulley wheel 20. At the bottom of the outer shell 15 of the crutcher a valve 21 is provided which discharges the liquid soap into the inlet opening 22 of the vacuum double drum dryer B.

The casing of the vacuum double drum dryer 10 is preferably made of cast iron and consists of a shell 23 which encloses the drying drums 24 and 25. At one end of the casing 23 is a head 26 is bolted to the casing, this head forming a compartment 27 which is enclosed by an end cover 15 28. The opposite end of the casing 23 is closed by another head 29 which forms a compartment 30 closed by an end cover 31. The trunnions 32 and 33 of each drum extend through the end heads 26 and 29 and are suitably journaled in 20 bearings 34 carried by these end heads. The compartment 27 encloses the gear drive for the drums which is indicated generally at 35 and is arranged to drive the drums in opposite directions at the same speed. The opposite compartment 30 encloses the steam connection 36 and the condensate outlet 37 of each drum, the steam inlets passing through the center of the corresponding trunnions 33 of the drums for heating the drums and the condensate being picked up by a siphon 38 in each drum and being discharged through the same trunnion which carries the corresponding steam connection. The steam and condensate connections can be of any usual and well known construction and hence a 30 detailed description is deemed unnecessary.

An essential element of the invention is the drying of the soap on the heated drums under vacuum and for this purpose the casing 23 is provided with a vapor outlet 39 which leads to 40 any suitable type of exhauster (not shown), but preferably of the condenser type.

To the bottom of the casing 23 is secured a hopper bottom 40 having a discharge opening 42 which is connected by an adapter 43 with the 45 inlet 44 of the plodder C. In order to prevent arching of the dried material in the bottom of the hopper 40 a breaking device is provided which preferably consists of a shaft 45 having a number of radial pins 46, this shaft being rotated in any suitable manner and being journaled in bearings in the ends of the hopper bottom 40.

The soap from the valve 21 is discharged through the inlet opening 22 of the vacuum dryer into a feed hopper 49 which consists of side walls 50 and 51 extending downwardly from the top of the casing 23 parallel with the drums 24 and 25 and terminating close to the upper surface of the drums; end walls 52 and 53 which likewise project downwardly from the top of the casing 23 immediately adjacent the opposite ends of the drums and are joined to the side walls 50 and 51; and a top plate 54 which is preferably integral with the side and end walls of the hopper and is preferably bolted to the top flange 55 of the casing 23. The liquid soap is retained in the hopper 49 and as the drums rotate the drum surfaces pick up a layer or film of the 70 liquid soap and dry these layers, these layers being subsequently scraped off and dropped in the form of sheets or ribbons to the lower hopper section 40. The liquid soap in the feeding hopper 49 can either be under atmospheric pres- 75

sure, or it can be under a partial vacuum. When a partial vacuum is maintained in the hopper, suitable suction pipes 48 are connected to the upper plate 54 of the feed hopper.

5 Inasmuch as a vacuum is maintained within the casing 23 and a lesser vacuum or atmospheric pressure maintained in the feed hopper 49, it is apparent that a seal must be provided between the bottom of the hopper walls 50, 51, 52 and 53 10 and the drying drums 24 and 25 and for this purpose adjustable packing means are provided which are preferably constructed as follows:

Each of the side walls 50 and 51 of the hopper is provided on its underside with a downwardly 15 facing groove or channel 56 which contains strips of packing 57 surmounted by a follower bar 58. This follower bar is pressed downwardly by a plurality of rods 59 which are spaced along each of the walls 50 and 51 and extend upwardly 20 through stuffing boxes 60 provided in the cover plate 54 of the feed hopper. In order to adjust the pressure exerted by the rods 59, each of these rods is provided with threads and is screwed 25 through a bracket 61 secured to the top or plate 54 of the feed hopper and is squared at its upper end so that by turning the rods they are adjusted vertically. This adjustment is held by a lock nut 62 on each rod. By adjusting the rods 59 up and down any desired pressure is applied 30 to the follower bar 58 and the packing 57. This packing provides a reliable seal between the sides of the hopper and the top of the drum surfaces so that the higher pressure on the liquid soap in 35 the feed hopper does not force the liquid soap under the side walls of the hopper.

In a similar manner the end walls 52 and 53 of the feed hopper are each provided at their lower ends with an inwardly opening channel 65, these channels 65 being each of V-shaped configuration, the ends conforming to the curvature 40 of the drums. In each of these channels 65 is arranged strips 66 of packing material backed by a follower bar 67. This follower bar is adapted to be moved outwardly by a series of cams 68 carried by the lower ends of rods 69, these rods 45 and cams being provided at suitably spaced intervals so that a uniform pressure can be exerted on the packing 66, this packing being pressed against the ends of the drums so as to provide a tight seal between the end walls of the feed hopper and the ends of the drums. The rods 69 extend upwardly through stuffing boxes 70 in the plate 54 of the feed hopper and the upper end 50 of each of these rods is squared as indicated at 71 so that each rod can be conveniently turned. In order to hold each rod in its adjusted position the upper end of each rod extends through a bracket 72 and suitable lock nuts 73 are provided between each rod and the corresponding 55 bracket.

As the drums rotate the film of soap on the heated drum is dried under vacuum. Thickness of the film adhering to the drum surface may be regulated by adjustment of the clearance between 60 the two drums, which is accomplished by having the bearings 34 of one of the drums movable in a horizontal direction at right angles to the drum axis. After the moisture content has been reduced to the desired extent the film on each drum 65 is scraped off by knives or doctor blades indicated generally at 75. Inasmuch as the construction of each of these scrapers is the same a description of one will be deemed to apply to both. Each of the scrapers 75 comprises a knife holder 76 which 70 is journaled in the end heads 26 and 29 of the

dryer and a pair of knives 77 and 78 are removably mounted on each knife holder 76 in any suitable manner. The knives 77 and 78 preferably each have a series of spaced square projecting cutting portions 79, as best shown in Fig. 8, and these overlap one another so that all the material is scraped from the drums. In order to adjust the pressure of the blades 77 and 78 on the drums the trunnions of each of the knife holders 76 and 77 extend through the end heads 10 26 and 29 of the dryer and are connected to levers 80 to the lower ends of which links 81 are pivoted. The other end of each of these links 81 is connected to an adjusting rod 82 which extends through a stuffing box 83 in the side wall of the 15 corresponding compartment 27 or 30. Each of the arms 80 is adapted to be adjusted by means of a hand wheel 84 which is arranged to move the corresponding rod 82 inwardly or outwardly, as may be required, each hand wheel having 20 threaded engagement with its rod for this purpose.

After the soap is stripped from the drying drums it is in condition to be finally packaged either by being formed into cakes or packed as 25 chips. If cakes are being produced, the soap is discharged into the plodder C. This plodder can be of any suitable form and as shown comprises 30 a casing 85 in which a horizontal packing screw 86 is journaled. The inlet opening 44 is above this screw and this screw receives and packs the soap flakes and discharges or extrudes the soap in the form of a solid stream through a discharge nozzle 87. The screw 86 is turned by means of 35 a suitable gearing 88 from a pulley 89 and the soap discharged from the nozzle 87 is cut into suitable lengths and pressed into bars.

In the event chips are desired the outlet of the adapter 43 can be provided with a continuous 40 discharge valve D, as shown in Fig. 9. Such valves generally consist of a cast iron rotor 90 enclosed in a cast iron casing 91 provided with bearings and having a gear drive (not shown), and a vacuum connection 92 for exhausting each 45 chamber before it enters into communication with the interior of the dryer casing.

In carrying out my improved process the perfume and coloring matter is added directly to the hot soap in the crutcher A. This mixes the perfume and coloring matter with the soap while it is still hot and fluid and thereby secures a very effective dispersal of the color and perfume throughout the soap mass without the necessity of milling the soap. Heretofore it has been wholly impracticable to attempt the addition of perfume or color at this stage as the perfume would be either destroyed or driven off by the succeeding usual drying operation and the color, if a soluble aniline color, which is preferred, was liable to be impaired or destroyed. By subsequently drying 50 in a vacuum double drum dryer I am able to add with advantage both the color and perfume and such other elements as may be desired to the hot soap in the crutcher without fear of destroying 55 or driving off these elements during the subsequent drying stage, since the soap is actually cooled while drying.

From the crutcher A the hot soap is discharged 60 into the feed hopper 49, this feed hopper being 65 sealed tight against both the tops and ends of both drums. These drums are rotated in the direction of the arrows shown in Fig. 1 and in rotating pick up a film of the soap and carry it 70 into the vacuum chamber of the casing 23, a 75

vacuum being maintained in this chamber through the exhaust outlet 39.

By drying the soap under vacuum it is unnecessary to cool the soap before being dried, as was necessary heretofore, and the present process thereby avoids the waste of heat incident to first cooling the soap and then heating it again in the dryer. Further, the tunnel dryer now generally used for the drying of soap operates at a temperature of about 140° F. to which temperature the soap ribbons from the chilling mills are exposed for a period of fifteen to twenty minutes. Large volumes of air are used in the tunnel dryer which is not only wasteful of heat and power but also would subject any perfume or coloring matter, if it had been added beforehand, to the danger of oxidation. Further, by drying in a vacuum dryer the chilling of the soap, which was required in order to harden the soap before being introduced into the tunnel dryer heretofore, is avoided and this loss of heat eliminated.

The important result, however, of drying under vacuum is the elimination of skin effect, the soap being dried under vacuum rapidly to a uniform moisture content of less than 20%, as required by the trade, thereby avoiding the necessity of subsequently storing or milling the soap. By drying under reduced pressure rapid evaporation is effected because the vapor pressure of the soap is higher than the pressure maintained in the dryer. This evaporation carries off heat and causes the soap to cool to a temperature approaching that corresponding to the boiling point of water under this reduced pressure, as evaporation takes place, thereby cooling and solidifying the soap without any expense for cooling water and at the same time accomplishing a removal of part of the moisture of the soap.

By using metal drums revolving at high speed a very thin film of soap is deposited on the drums and from this thin film the water vapor can readily escape without any skin effect. Skin effect is caused by such rapid evaporation from a surface to a layer of wet material that the amount of water evaporated from the surface is greater than the amount of moisture which travels from the center of the layer by diffusion. Herby a skin of dry material is formed on the surface which inhibits or greatly retards further diffusion of moisture from the center of the layer. The rate of diffusion varies with the thickness and the moisture gradient between center and surface of the layer. By revolving the drums at high speed the thickness of the layer is reduced to such an extent that the necessity for diffusion is greatly reduced.

By heating the drums with live steam, heat is transferred through the metal. A small amount of heat so transferred and absorbed by the thin film of soap maintains a temperature at which the vapor pressure of the soap is materially higher than the pressure maintained in the dryer. As a result of the very slight thickness of the film and the resultant ease with which the moisture can travel through the film and escape, a rapid evaporation of the moisture in the film of soap takes place, the moisture content of the film remains uniform and the temperature of the film cannot rise sufficiently to cause it to melt and liquefy again. Notwithstanding the fact that the steam used for heating the drums is at a higher temperature than the liquid soap fed to the dryer, this soap is cooled and its tempera-

ture maintained sufficiently low to remove it from the drum surface in condition for final packaging and with sufficient residual moisture to conform to present commercial standards (5-20% moisture content).

As a result, by drying under vacuum, the soap film dries very quickly and the drums can be rotated very rapidly, at a speed from 50 to 150 R. P. M. and the film deposited on the drum be very thin, tests indicating that the initial thickness of the film should not exceed .0015 of an inch. This permits the use of very small drying drums and a vacuum drum dryer suitable for handling a thousand pounds per hour of toilet soap can be made with drums 18 inches in diameter and 36 inches in length. This, it will be appreciated, greatly economizes in floor space and the cost of apparatus as compared with the tunnel dryer heretofore necessary, the hot air circulation system for this tunnel dryer, to say nothing of the elimination of the cooling rolls, milling rolls and mixing apparatus incident to the prior process.

Since the perfume and coloring matter has been added to the soap before drying and since the film of soap on the drums dries without skin effect and has a uniform moisture content it is immediately available for packaging in its final form. For this purpose the outlet of the vacuum drum dryer is directly connected to the plodder 30 C when bar soap is desired, the soap flakes being pressed into a solid mass by the packing screw in this plodder and extruded through its outlet orifice. The soap from the plodder is stamped into bars. If flake soap is desired the outlet of 35 the vacuum dryer is equipped with the continuous rotary discharge valve shown in Fig. 9 from which the chips can be directly packaged.

The cost of the equipment for operating in accordance with the present invention is, of course, far less than the expensive machinery heretofore used and as an estimate of the saving in operating cost the following comparative figures are offered. The estimates are made on equipment for drying 1000 pounds per hour. With a tunnel dryer and its accessory equipment of milling rolls, plodder, etc. the following would be required:

Floor space	810 square feet
Power	65 horse power
Steam	460 pounds per hour
Cooling water	25 gallons per minute
Labor	\$1.80 per hour

With a vacuum dryer the following are required 55 in an actual installation:

Floor space	200 square feet—a saving of 610 square feet
Power	25 horse power—a saving of 40 horse power
Steam	230 pounds per hour—a saving of 230 pounds per hour
Cooling water	15 gallons per minute—a saving of 10 gallons per minute
Labor	\$.90 per hour—a saving of 50%

From the foregoing it is apparent that the present invention provides a method for drying soap which permits of adding the perfume and coloring matter to the soap while it is still liquid and thereafter dry the soap and deliver it to a plod- 75

der or packaging machine in continuous process. Furthermore, the present process eliminates the steps required in prior processes of cooling the soap on a cooling drum; heating for a substantial period of time in a tunnel dryer; storing the soap flakes to partially equalize the remaining moisture evenly throughout the soap flakes; mixing of the soap flakes with perfume and coloring matter and milling of the soap for further equalization of moisture and uniform distribution of perfume and color. Further, the cost of the equipment necessary for carrying on the present invention and the cost of operation is but a fraction of the cost of the equipment necessary for drying soap according to prior processes and very much less floor space is required.

While I have shown one embodiment of my invention it will be appreciated that the apparatus can be varied widely to adapt it to different conditions and the invention is therefore not to be construed as being limited to any particular form or step shown but is to be accorded the full

range of equivalents comprehended by the following claim.

I claim as my invention:

The method of treating soap under vacuum which consists in withdrawing hot soap in liquid form and at a temperature substantially above the boiling point of water under said vacuum and having a high percentage of solids directly from a soap kettle, admitting the withdrawn soap in undiluted form to a vacuum chamber, applying a thin film of said soap, not exceeding .0015 of an inch, while in said vacuum chamber to a relatively small heated drying drum rotating at from 50 to 150 R. P. M., thereby to reduce the moisture content and cool the soap, cooling said film to a temperature near the boiling point of water under said vacuum and reducing the moisture content of said film on said drum uniformly to less than 20% without skin effect, and scraping the soap from said surface in substantially solid form in condition to be directly packed in bar or flake form.

ADOLPH F. THAL.
